SWITCH CLOSING MECHANISM

Thellwell R. Coggeshall, Bala Cynwyd, Herman B. Dhomau, Philadelphia, and Carl Thumim, Yeadon, Pa., assignors to General Electric Company, a corporation of New York

Application July 9, 1940, Serial No. 344,530

7 Claims. (Cl. 175—375)

Our invention relates to operating mechanisms and more particularly to cam operating mechanisms wherein a motor-driven cam is operatively related to a thrust-transmitting structure for effecting a working stroke. Specifically, this invention is an improvement on the arrangement disclosed and claimed in United States Letters Patent 2,131,603, granted September 27, 1938, upon an application of Carl Thumim and assigned to the assignee of the present application.

In the application of cam operating mechanisms of the above-described character to means, such as, for example, a circuit breaker operable between open and closed circuit positions, it is desirable that the cam assume a predetermined angular position at the beginning of the closing operation with respect to the means to be operated. This is particularly important where the circuit-breaker mechanism is of the trip-free type wherein a collapsible linkage normally maintained in the thrust-transmitting position by tripping means coacts directly with a motor-driven cam. The operating or working stroke in this case is the circuit-closing stroke at the end of which the motor is automatically deenergized. Since the closing stroke must be positive and fast, a comparatively large amount of kinetic energy is stored in the rotating mass at the end of the stroke, so that considerable difficulty in stopping the arrangement at a predetermined position obtains.

High-speed means have been proposed for stopping the cam in the same angular position by allowing it to overtravel and then providing means, such as centering springs and the like, to return the cam to the desired position. However, when mechanisms of this type are used in high-speed reclosing circuit breakers, the delay in allowing the cam to overtravel and then being reset by spring means or the like considerably increases the minimum reclosing time obtainable.

High-speed braking has also been proposed for stopping the cam but, due to the large amount of energy involved, damage to the mechanism often occurs since, in the prior arrangements, the heavy torque end of the mechanism which it was desired to stop at a predetermined position was the one to which the braking means was applied. It would be desirable to provide an operating mechanism which is accurately timed from the high torque end thereof to stop the cam at a predetermined position without the delay inherent in the arrangements including the cam-centering means of the prior art.

Accordingly, it is an object of our invention to provide an improved cam-operating mechanism of uniformly high-speed and efficient operation which is simple and rugged in construction, reliable and positive in its resetting action and which overcomes the difficulties set forth above.

It is another object of our invention to provide a cam-operating mechanism for a circuit breaker requiring a predetermined angular position at the beginning of the closing operation in which the position is timed from the heavy torque end of the apparatus so as to apply high-speed braking means on the low torque end thereof.

Still another object of our invention is to provide a cam operating mechanism for an electric circuit breaker which eliminates any possibility of nonuniform operation due to such variables as voltage and flux-decay conditions.

Further objects and advantages of our invention will become apparent as the following description proceeds and the features of novelty which characterize our invention will be pointed out with particularity in the claims annexed to and forming a part of the specification.

For a better understanding of our invention, reference may be had to the accompanying drawing in which the single figure thereof is a partly diagrammatic view of a cam operating mechanism embodying the present invention shown in the open preset position in readiness for a working stroke.

Referring now to the drawing, the operating mechanism illustrated therein comprises an electric motor 10 operatively connected through suitable gearing 11 and an operating shaft diagrammatically indicated at 12 to a rotatable cam 13. The cam 13 is provided with a suitably designed operating face 13' and is secured to the shaft 12 so as to be rotated in a counterclockwise direction, as shown by the arrow, upon energization of the motor 10.

The means to be actuated is generally indicated at 14 and may comprise the operating rod 45 of an electric circuit breaker, for example. In the solid lines of the drawing, the rod 14 is shown in the open position of the circuit breaker, not shown, and is operatively related to the cam 13 through a collapsible thrust-transmitting linkage indicated at 15. The linkage is normally held in the thrust-transmitting position by a tripping means indicated at 16. With the linkage in the open preset position shown, one revolution of the cam 13 is effective to cause a working stroke, the completion of which is indicated by

the linkage and operating rod in the dotted-line positions.

The thrust-transmitting structure can be of any suitable design as will be understood by those skilled in the art. By way of example, we have shown a thrust-transmitting structure comprising a main toggle 17-17 including a roller 19 which coacts with the operating face 13' of the cam 13. The toggle link 17 is pivotally connected at one end at 20 to a guide link 21 having a fixed pivot 22. The toggle link 18 is pivotally connected at 23 to a lever 24, which is, in turn, pivotally connected at 25 to the breaker-operating rod 14. The pivot 26 of the toggle link 17 is normally held fixed by the tripping means 16 so that, when toggle 17-17 is straightened at its knee joint 26 by the cam 13, the lever 24 is rotated about its fixed pivot 21 in a clockwise direction to lower the operating rod 14.

The tripping means 16 specifically comprises a tripping toggle 28-29 connected respectively to the main toggle pivot 26 and to a fixed pivot 30. A latch 31, which is rotatively mounted at 32, is adapted to engage a roller 33 carried by an extension 29' of the toggle link 28. An extension 29' of the toggle link 28 coacting with the fixed pivot 30 maintains the toggle in an underset position so that, when the latch 31 is moved out of restraining engagement with respect to roller 33, the toggle 28-29 collapses under the thrust exerted at the pivot 26. Thereafter, the toggle 17-18 is no longer restrained in a thrust-transmitting position but is free to collapse, permitting reverse movement of the operating rod 14 to the solid-line position shown under bias of energy-storage means 34, shown in the drawing as a suitable opening spring.

The latch 31 can be controlled in any suitable manner as by the conventional tripping solenoid 35 or by independent manual means indicated at 36.

The dotted position in the drawing illustrates the thrust-transmitting linkage in the restraining or closed-circuit position with respect to the operating rod 14. In this position, the knee joint 26 of the toggle 17-18 is overset and engages a stop member 37. The linkage is thereby effectively locked in this position with respect to the thrust of spring 34 or other opening means tending to rotate lever 24 clockwise as long as the toggle pivot 26 is held by the above-described tripping means 16. When the tripping means is actuated in the manner above indicated, the tripping toggle 28-29 is no longer restrained by the latch 31 and buckles, permitting the toggle pivot 26 to move about the fixed pivot 21 in a counterclockwise direction under the influence of the reacting forces, such as spring 34, tending to cause opening movement of the breaker rod 14. When the toggle 17-18 has collapsed and the lever 24 is rotated counterclockwise to the solid position indicated in the drawing wherein the roller 19 again engages the operating face or "low" point of the cam 13, the tripping toggle 28-29 is again stretched and extended so that the roller 33 rides beneath the latch 31. In this position, the mechanism is reset and in readiness for another cam operation.

The motor-control system generally designated at 38 is adapted to deenergize automatically the motor and other apparatus to be described hereinafter after a working stroke of cam 13 and to prevent a subsequent operation in the absence of a further positive control operation by the operator. This control system per se forms no part

of the present invention and is described and claimed in United States Letters Patent to Thumim et al., 2,094,478, granted September 26, 1937, and assigned to the assignee of the present application.

The control system comprises a controlled source of power indicated at 39 from which the motor 10 and a solenoid 40 to be described hereinafter are energized through a suitable contactor 41-41'. The operating coil 42 for contactor 41-41' is adapted to be energized through an operating switch 43 and a limit switch 44. Accordingly, in order to initiate simultaneously the energization of the motor 10 and solenoid 40, switch 43 must be closed, thereby causing contactor 41-41' to close. This operation seals the circuit of the contactor coil 42 through auxiliary contacts 45 in so far as the operation of switch 43 is concerned so that the motor will not be de-energized in the middle of the operating stroke by the opening of switch 43.

The motor is automatically deenergized at the end of the stroke by means of a member 46 secured to the cam shaft 12. The member 46 is provided with a pin 47 which picks up the loosely pivoted arm 48. At the end of the stroke, the member 46 lifts the pivoted switch member 49 so as to open contacts 44 and cause deenergization of coil 42 of contactor 41-41'. At the same time, an auxiliary switch 46 is closed, thereby energizing a coil 51 in the event that the switch 43 is still closed. The switch member 49 is accordingly held in the upper position through the co-acting armature 52. It is, therefore, necessary that manually operable switch 43 be opened and again closed before a second operation can be initiated, thereby precluding repeated operations or "pumping" of the mechanism. It will, of course, be understood that switch 43 referred to hereinbefore may be a manually operable switch or may be controlled by suitable automatic means if desired.

For the most efficient operation of cam 13, it is clear that the "dwell" or low region should be limited to a minimum. On the other hand, if the extent of the low region of the cam is very small, the cam must be stopped for the next operation within very narrow limits. Due to inertia of moving parts, a certain amount of overtravel is unavoidable and the amount of overtravel permitted determines the extent of the low region of cam 13. It is obvious from the drawing that the high point of cam 13 clears the roller 19 when the toggle 17-18 moves to its overset position indicated by the dotted lines. If the cam were instantly stopped at that point, roller 19 could engage the "low" point of the cam immediately upon tripping so that the tripping means 16 would immediately reset. This, therefore, provides the main reason for limiting the overtravel of the cam since, if roller 19 were to drop to an intermediate point on the cam face 13' instead of the "low" portion, the tripping means 16 could not be reset. Of course, if the cam were designed to have a "low" point or "dwell" period of 180 degrees, the resetting of the tripping means could safely be accomplished but such cam design is obviously unsatisfactory since but 180 degrees remain for the working phase. Furthermore, with a longer "dwell" which would permit a wide range of positions where the cam could stop, there would be a large variation in closing time, which would be especially objectionable where the circuit breaker is used for synchronizing.

Various means have been employed for caus-

ing the cam to stop at a predetermined position, the most successful of which heretofore allowed the cam to overtravel, after which it was returned by suitable centering springs or the like to the desired position. It is obvious that such overtravel and return inherently introduces a delay which limits the reclosing time of a high-speed circuit breaker. By means of this delay, of course, there is ample time for the tripping means 16 to reset at a predetermined point on the cam.

The present invention discloses a new means for causing the cam to come to rest at approximately the same position after motor cutoff irrespective of the speed of the motor due to variable voltage conditions and irrespective of the momentum of the moving parts, thus permitting the "low" or ineffective portion of the cam periphery to be reduced to a working minimum. Furthermore, the present invention eliminates the inherent delay due to overtravel and return of the cam but instead causes stopping of the cam at a predetermined point so that resetting of the tripping means 16 is assured. Furthermore, the hazard of strained working parts and the indeterminate final cam position due to unavoidable operation of the control motor on varying voltages is completely eliminated.

To this end, we provide means for causing the cam 13 to assume a predetermined position at the end of each working stroke which is determined by timing means at the cam end or heavy torque end of the operating mechanism so as to stop the high-speed low-torque end comprising motor 10, whereby no straining or danger to the working parts of the apparatus is caused while enabling the operating mechanism to be stopped in a very short interval of time. Accordingly, we have provided motor 10 with a multiple disk brake generally indicated at 53 comprising alternate plates 54 and 55, respectively, the former keyed to the motor shaft while the latter are keyed to the stationary support 56. End pressure applied to alternate plates 54 and 55 through thrust plate 57 causes an enormous braking action on the shaft of motor 10. This pressure is exerted by a spring 58 acting on lever 59 pivotally supported at 60 and arranged to engage thrust plate 57. Multiple disk brake 53 is so designed as to stop high-speed motor 10, which preferably operates between 4,000 and 12,000 R. P. M., within one to six revolutions which, of course, means stopping cam 13 within very narrow limits.

Multiple disk brake 53 is released by means of solenoid 40 which causes clockwise rotation of pivotally mounted lever 59 against the force of brake spring 58. Since solenoid 40 is energized at the same time as motor 10, brake 53 is always released when motor 10 is energized. In order to time accurately the operating mechanism from the high-torque end to cause accurate stopping of cam 13 at the end of the working stroke, we provide an auxiliary timing cam 61 provided with a notched portion 61a cooperating with the tip 59a of lever 59. When motor 10 and solenoid 40 are energized through motor control system 38, the tip 59a of lever 59 is pulled away from timing cam 61 which is caused to rotate with cam shaft 12. Thereafter, even though motor 10 and solenoid 40 are deenergized, spring 58 cannot cause reapplication of multiple disk brake 53 until cam 61 has rotated sufficiently to allow tip 59a of lever 59 to reenter notch 61a and motor 10 will coast until this condition occurs at

which time brake 53 is applied, thereby stopping cam 13 within very narrow limits.

The operation of the operating mechanism for one working stroke will be considered with reference to the positions of the various parts shown in solid lines in the drawing. By closing switch 43, contactor coil 42 is energized so as to close contactor 41-41' and energize motor 10 and solenoid 40. This operation causes lever 59 to be removed from notch 61a of timing cam 61 and releases multiple disk brake 53. Motor 10 then drives cam 13 through gearing 11, forcing the collapsible thrust-transmitting linkage 15 upwards to assume the dotted position shown in the drawing. This results in the charging of opening spring 34 and the closing of the circuit breaker, not shown, associated with operating rod 14. When roller 19 reaches the highest point of cam 13, the toggle linkage 17-18 has passed above center and against the toggle stop 37 so that, through spring means 34, the linkage is locked in the overcenter position until trip latch 31 releases the latch for the opening stroke. Shortly after the toggle 17-18 goes over center, the member 46 causes pivoted arm 48 to open limit switch 44, whereupon contactor coil 42 is de-energized and contactor 41-41' causes de-energization of motor 10 and solenoid 40. The use of a separate switch for motor 10 and solenoid 40 embodied in contactor 41-41' prevents motor 10 from acting as a generator when coasting to continue energization of solenoid 40. The brake spring 58 tends to return lever 59 to its normal position, causing braking operation of multiple disk brake 53. However, timing cam 61 engaging with tip 59a of lever 59 holds brake 53 in the released position until cam 13 has rotated far enough for the roller 19 to drop past the tail of cam 13. After a few degrees additional rotation of cam 13, lever 59 drops off the surface of timing cam 61 into notch 61a and the pressure of spring 58 is applied to the plates 54-55 of multiple disk brake 53, stopping motor 10 within a few revolutions and, consequently, stopping timing cam 13 within a very few degrees of rotation so as to position it accurately for the next operation of the mechanism.

In case the control circuit is lost during a closing operation, the pressure of breaker opening spring 34 applied through linkage 15 to cam 13 will cause rotation of motor 10 and main cam 13 in a reverse direction to allow the breaker to open. During the opening motion of the breaker, pressure is withheld from the multiple disk brake 53 by timing cam 61, which holds lever 59 in the released position until the breaker, not shown, has reached the open position. At this point, the tip 59a of lever 59 drops off timing cam 61 to allow brake 53 to be applied, thereby positioning cam 13 for the next closing operation of the mechanism.

Thus, by insuring a predetermined starting position for cam 13, a uniform operating time is possible as well as high-speed operation of the cam due to the fact that the tripping means is already reset. Furthermore, by eliminating the overtravel and return means of prior art arrangements, the speed of operation has been considerably increased, particularly when used in connection with reclosing circuit breakers.

While we have shown and described particular embodiments of our invention relating to operating mechanisms, we do not desire our invention to be limited to the arrangements shown and described for it will be obvious to those skilled in

the art that changes and modifications may be made without departing from our invention and we, therefore, aim in the appended claims to cover all such changes and modifications as fall within the true spirit and scope of our invention.

What we claim as new and desire to secure by Letters Patent of the United States is:

1. In an operating mechanism comprising a motor and a rotatable cam driven thereby, means adapted to be actuated from one position to another position by said cam, said cam at the initiation of said operation being in a preferred predetermined position with respect to said actuated means, means for deenergizing said motor upon completion of said cam operation but prior to the time said cam reaches said predetermined position, and means operative upon further rotation of said cam to said predetermined position after deenergization of said motor for causing said motor to be stopped quickly so that said cam assumes said predetermined position. 10
2. In an operating mechanism for a circuit breaker, a motor, means actuated thereby for effecting in a cycle of operation a circuit-closing operation, means for deenergizing said motor at the end of said cycle, braking means for said motor released simultaneously with the energization of said motor, and means for causing said braking means to remain ineffective upon deenergization of said motor until a predetermined position of said first-mentioned means has been obtained. 15
3. An operating mechanism for a circuit breaker comprising a motor and a rotatable cam driven thereby, means actuated by said cam for closing said circuit breaker, a brake for said motor and spring means for holding said brake in braking position, means for energizing said motor and simultaneously releasing said brake for initiating the closing operation of said circuit breaker, means for deenergizing said motor at the end of said closing operation, and means for causing said braking means to remain in the released position upon deenergization of said motor until a predetermined position of said cam has been obtained. 20
4. In an operating mechanism comprising a low-speed heavy-torque portion including a cam member and a high-speed low-torque portion including a motor, means adapted to be actuated from one position to another position by said cam, said cam at the initiation of said operation being in a preferred predetermined position with respect to said actuated means, and means for stopping said cam in said predetermined position comprising braking means applied to said low-torque portion of the apparatus in response to the position of the high-torque portion of the apparatus. 25
5. In an operating mechanism for an electric circuit breaker, a motor and a rotatable cam driven thereby, means adapted to be actuated from one position to another position by said cam for closing said circuit breaker, a brake for said motor and spring means for holding said brake in braking position, means for energizing said motor and simultaneously releasing said brake for initiating the closing operation of said circuit breaker, means for deenergizing said motor at the end of said closing operation, and a timing cam driven by said motor so constructed and arranged to operate with said pivoted lever and prevent said braking means from becoming effective upon deenergization of said motor until a predetermined position of said cam has been attained. 30
6. In an operating mechanism for an electric circuit breaker, a motor and a rotatable cam driven thereby, means adapted to be actuated from one position to another position by said cam for closing said circuit breaker, a brake for said motor, a pivoted lever operatively connected to said brake and spring biased in a direction normally to hold said brake in said braking position, a solenoid operatively connected to said pivoted lever so as to overcome said spring bias and release said brake upon energization thereof, a control circuit for simultaneously energizing said motor and solenoid to initiate the closing operation of said circuit breaker, means associated with said control circuit for deenergizing said motor and said solenoid at the end of said closing operation, and a timing cam driven by said motor so constructed and arranged to operate with said pivoted lever and prevent said braking means from becoming effective upon deenergization of said motor until a predetermined position of said cam has been attained. 35
7. An operating mechanism for an electric circuit breaker comprising a motor and a cam shaft driven thereby through reduction gearing, an operating cam on said cam shaft, means adapted to be actuated by said operating cam for closing said circuit breaker, said operating cam at the initiation of said stroke being in a predetermined angular position with respect to said means, a brake for said motor, a pivoted lever operatively connected to said brake and spring biased in a direction normally to hold said brake in said braking position, a solenoid operatively connected to said pivoted lever so as to overcome said spring bias and release said brake upon energization thereof, a control circuit for simultaneously energizing said motor and solenoid to initiate the closing operation of said circuit breaker, said control circuit being arranged to deenergize said motor and said solenoid at the end of said closing operation, and a timing cam on said cam shaft provided with a notch for preventing said pivoted lever from returning to said braking position upon deenergization of said solenoid until the end of said lever engages said notch, whereby said predetermined angular position of said operating cam is assured. 40
8. In an operating mechanism for an electric circuit breaker, a motor and a rotatable cam driven thereby, means adapted to be actuated from one position to another position by said cam for closing said circuit breaker, a brake for said motor and spring means for holding said brake in braking position, means for energizing said motor and simultaneously releasing said brake for initiating the closing operation of said circuit breaker, means for deenergizing said motor at the end of said closing operation, and a timing cam driven by said motor so constructed and arranged to operate with said pivoted lever and prevent said braking means from becoming effective upon deenergization of said motor until a predetermined position of said cam has been attained. 45
9. In an operating mechanism for an electric circuit breaker, a motor and a rotatable cam driven thereby, means adapted to be actuated from one position to another position by said cam for closing said circuit breaker, a brake for said motor and spring means for holding said brake in braking position, means for energizing said motor and simultaneously releasing said brake for initiating the closing operation of said circuit breaker, means for deenergizing said motor at the end of said closing operation, and a timing cam driven by said motor so constructed and arranged to operate with said pivoted lever and prevent said braking means from becoming effective upon deenergization of said motor until a predetermined position of said cam has been attained. 50
10. In an operating mechanism for an electric circuit breaker, a motor and a rotatable cam driven thereby, means adapted to be actuated from one position to another position by said cam for closing said circuit breaker, a brake for said motor and spring means for holding said brake in braking position, means for energizing said motor and simultaneously releasing said brake for initiating the closing operation of said circuit breaker, means for deenergizing said motor at the end of said closing operation, and a timing cam driven by said motor so constructed and arranged to operate with said pivoted lever and prevent said braking means from becoming effective upon deenergization of said motor until a predetermined position of said cam has been attained. 55
11. In an operating mechanism for an electric circuit breaker, a motor and a rotatable cam driven thereby, means adapted to be actuated from one position to another position by said cam for closing said circuit breaker, a brake for said motor and spring means for holding said brake in braking position, means for energizing said motor and simultaneously releasing said brake for initiating the closing operation of said circuit breaker, means for deenergizing said motor at the end of said closing operation, and a timing cam driven by said motor so constructed and arranged to operate with said pivoted lever and prevent said braking means from becoming effective upon deenergization of said motor until a predetermined position of said cam has been attained. 60
